DESIGN.

C. BLESCH.

BURIAL CASKET PLATE.

APPLICATION FILED MAY 14, 1917.

51,039.

Patented July 17, 1917.

Inventor:

Charles Blesch,
by A. T. Neffle,
via Attorney.

UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET PLATE.

51,039.

Specification for Design.

Patented July 17, 1917.

Application filed May 14, 1917. Serial No. 168,608. Term of patent 14 years.

To all whom it may concern:

Be it known that I, CHARLES BLESCH, a citizen of the United States, residing at Newport, in the county of Campbell and State of Kentucky, have invented a new, original, and ornamental Design for Burial-Casket Plates, of which the following is a specification, reference being had to the accompanying drawing, forming part thereof.

My new, original and ornamental design for a burial-casket plate is shown in the accompanying drawing, in which,

The figure is a front elevation of a burial-casket plate, showing my new design.

I claim:

The ornamental design for a burial-casket plate, substantially as shown.

CHARLES BLESCH.

Witnesses:

HERBERT S. BRIDGE,

HENRY F. SCHROEDER.
